POTENTIAL RATIO-CONTROLLED
AMPLIFIER

Clarence W. Hansell, Port Jefferson, N. Y., assignor to Radio Corporation of America, a corporation of Delaware

Application December 10, 1942, Serial No. 468,449

14 Claims. (Cl. 250—20)

My present invention relates generally to circuits for obtaining control of the distribution of current between at least two electron collection electrodes, and more specifically to an electrically controlled device for controlling the distribution of current between a pair of anodes substantially in accordance with the ratio of two controlled potentials, or currents, independently of their amplitude.

In my application Serial No. 469,647 filed Dec. 21, 1942, I have disclosed and claimed various devices for controlling the division of a current into parts according to the ratio of two controlled currents. Briefly, in that application the circuit arrangements function in accordance with the principle that when a magnetic field in a vacuum is made strong enough substantial electron motions can take place only in the directions parallel to the magnetic field. Any component of motion in other directions is overcome, because the magnetic field bends the path of motion in these directions back to the axis from which they started. More specifically a pair of crossed magnetizing coils, within which there is located a cathode and an arrangement of anodes, are provided, and the distribution of electron current to the anodes is controlled by regulating the direction of the field. The latter, in turn, is controlled by the ratio of currents in the magnetizing coils independently of the amplitude of these currents.

Accordingly, it may be stated that it is one of the main objects of my present invention to provide a method of electrically controlling the distribution of current between a pair of anodes in accordance with the ratio of two controlled potentials independently of their amplitude.

In my aforesaid application there is also disclosed the application of the electron current distribution method to a frequency, or phase, modulation receiver which does not employ a carrier amplitude limiter. In general, the frequency modulation detector of such a receiver is followed by a current ratio-controlled amplifier device whereby the receiver is adapted to be nearly unresponsive to carrier amplitude variations.

Accordingly, it may be stated to be another important object of the present invention to provide a frequency, or phase, modulation receiver wherein the usual type of balanced frequency modulator detector is followed by a potential ratio-controlled amplifier thereby making it unnecessary to apply a special amplitude limiter stage in a frequency modulation receiver.

In this application, wherever used, the generic

terms "angular velocity-modulated carrier waves" and "timing-modulated carrier waves" are to be understood as covering either frequency or phase modulated carrier waves, or combinations thereof. In this connection it is pointed out that frequency modulations of a carrier current in which the higher modulation frequency currents are emphasized or increased with respect to lower frequencies results in a type of modulation which is more accurately described as phase modulation than as frequency modulation. Thus, the above terms are intended to include any form of frequency modulation, or any form of phase modulation.

15 A still more specific object of my present invention is to provide frequency and phase modulation receivers without amplitude limiters, but having over-all characteristics similar to those obtainable through the use of limiters. In accomplishing this purpose I provide subsequently to a conventional balanced frequency modulation detector, a potential ratio-controlled amplifier which is insensitive inherently to amplitude variations.

25 In using the phrase "potential ratio-controlled" I have assumed that the word "ratio" has no other dimension or significance than magnitude. Consequently, I wish it to be understood that the expression "potential ratio" inherently signifies the ratio of magnitude of two potentials.

30 Other objects of the invention are to improve generally the simplicity and efficiency of frequency and phase modulation receivers, but more especially to eliminate any need for an amplitude limiter.

35 The novel features which I believe to be characteristic of my invention are set forth in particularity in the appended claims; the invention 40 itself, however, as to both its organization and method of operation will best be understood by reference to the following description, taken in connection with the drawing, in which I have indicated diagrammatically a circuit organization 45 whereby my invention may be carried into effect.

In the drawing:

Fig. 1 shows a circuit embodying the invention.

Fig. 2 is a partly sectioned view of the interior of an amplifier tube adapted for use in 50 the circuit of Fig. 1,

Fig. 3 is a sectional view along line 3—3 of Fig. 2 looking in the direction of the arrows,

Fig. 4 is a sectional view along line 4—4 of Fig. 2, looking in the direction of the arrows.

55 Referring, now, to the accompanying draw-

ing, wherein like reference characters in the different figures designate similar circuit elements, the circuit of Fig. 1 shows the invention applied to a frequency modulated carrier wave (FM) receiver. More specifically, the potential ratio-controlled amplifier tube 1 is utilized subsequently to the balanced FM detector network. The conventional special amplitude limiter network, at any point prior to the detector network, is accordingly dispensed with, or, if preferred, reduced in its range of operation. The following discussion of the problem sought to be solved by this invention is given.

In receivers for signals transmitted by means of frequency and phase modulated radio waves, of which reception of FM radio broadcast programs is a common example, there are undesired amplitude modulations of carrier currents in the receivers which tend to add unwanted noise to the receiver output. These amplitude modulations usually are present because of hum modulations in the transmitter; because of interfering radiations produced from the space circuit due to natural causes, or due to operation of electrical equipment of many kinds; because of hum and microphonic noises in the receivers; because of thermal agitation and shot effect noises in early circuits in the receivers; and because of insufficient uniformity, or flatness of response, of selective circuits within the frequency band occupied by the frequency and phase modulated waves and currents. In the prior art it has been customary to employ an amplitude limiter for removing amplitude modulations from the carrier current before the carrier current is applied to a frequency or a phase modulation demodulator. By removing amplitude modulations with a limiter it has been found possible to make a very substantial improvement in signal to noise ratio in the output of frequency and phase modulation receivers.

The following patents are given to illustrate the state of the prior art of receiving frequency and phase modulated carrier waves. It is to be understood that the presently disclosed potential ratio-controlled amplifier circuit may be used in any of these prior systems. This invention is of broad application, and may be utilized with other apparatus of widely varying characteristics including any of the prior systems described in the following patents. The latter are arranged in the order of filing of the respective applications: U. S. Patent No. 2,057,640, Conrad, filed Mar. 17, 1927; U. S. Patent No. 1,941,447, Armstrong, filed May 18, 1927; U. S. Patent No. 1,819,508, Hansell, filed Aug. 11, 1927; U. S. Patent No. 1,794,932, Usselman, filed Sept. 1, 1927; U. S. Patent No. 2,013,847, Hansell, filed Oct. 2, 1928; U. S. Patent No. 1,803,504, Hansell, filed Oct. 5, 1928; U. S. Patent No. 1,867,567, Hansell, filed Feb. 1, 1929; U. S. Patent No. 1,941,069, Armstrong, filed Jan. 24, 1933; U. S. Patent No. 2,121,103, Seeley, filed Oct. 17, 1935; U. S. Patent No. 2,180,736, Hansell, filed May 5, 1936; U. S. Patent No. 2,205,762, Hansell, filed Nov. 16, 1936; U. S. Patent No. 2,179,182, Hansell, filed Nov. 27, 1936; U. S. Patent No. 2,207,541, Hansell, filed Jan. 18, 1939; U. S. Patent No. 2,243,702, Hansell, filed May 19, 1939; and U. S. Patent No. 2,249,425, Hansell, filed Mar. 27, 1940.

The limiters of the prior art have usually been some sort of amplifier so designed, adjusted and operated that changes in input power gave little, if any, change in output power. These limiters required some input power level to be exceeded

before a satisfactory limiting condition was reached, and often they showed a reduction in output power if the input power became relatively high. In designing limiters it has been found that the amplifier-limiter system preceding the demodulator must be capable of great over-all amplification, or increase of power, when weak signals are to be received. To provide for this great amplification and for adequate limiting at the same time, it has been necessary so to construct frequency and phase modulation receivers that they have been relatively expensive. Because of this high cost the use of frequency and phase modulation has not increased as rapidly as might be desired, and some receiver manufacturers, to avoid the cost, have sold frequency modulation receivers to the public which omitted amplitude limiters even though such receivers do not adequately suppress amplitude modulation noise.

In my application Serial No. 423,881, filed December 22, 1941, there are disclosed various types of demodulators for frequency and phase modulation which when provided with a correct level of input power, are inherently unresponsive to the effects of amplitude modulation so that no limiter is required. In the present application the frequency or phase modulation receiver may be of any of the prior systems noted, save that they do not include a special amplitude limiter prior to the detector. In accordance with my present invention the detector may be of any well-known form. Instead of constructing the demodulator to be inherently unresponsive to amplitude modulation, I provide an amplifier circuit subsequent to the demodulator, which amplifier circuit is unresponsive to the amplitude modulation. The demodulator tubes are shown as consisting of a pair of opposed diode rectifiers 2 and 3. The FM signals, regardless of the source thereof, are applied to an input transformer 4. One end of the secondary winding of the transformer is connected to the junction of a pair of series-related series resonant circuits. One of these series resonant circuits consists of condenser 5 and coil 6. The other series resonant circuit consists of coil 7 and condenser 8. The junction of coil 6 and 7 is connected to the aforementioned end of the secondary winding of transformer 4. The anode of rectifier 3 is connected to condenser 5, and to the opposite end of the secondary winding of transformer 4 through a resistor 9. The anode of rectifier 2 is connected to condenser 8, and to the last mentioned end of the secondary winding through resistor 10.

The output load resistors of the rectifiers 2 and 3 are designated by numerals 11 and 12 respectively. Each of these load resistors is bypassed by an appropriate radio frequency by-pass condenser. The junction of resistors 12 and 11 is connected to the junction of coil 6 and 7. The balanced FM detector disclosed in Fig. 1 is essentially that described by E. H. Armstrong in his U. S. Patent 1,941,069, granted Dec. 26, 1933. Briefly, in that circuit the source of FM waves, which may be the output circuit of the prior intermediate frequency (I. F.) amplifier of a superheterodyne receiver, has its FM voltage applied to the pair of series resonant circuits 5-6 and 7-8. Each of these series resonant circuits includes a respective resistor. Each series resonant circuit is connected in shunt with its respective diode rectifier. As pointed out in

the Armstrong patent, the series resonant circuits are oppositely mistuned by equal frequency amounts with respect to the mean frequency of the applied FM waves. The cathode circuits of the rectifiers are connected so as to respond cumulatively for frequency variations. The resistors 9 and 10 are used to provide a substantially constant current, for any constant input potential, to the discriminator series resonant circuits within the signalling band, even though the series resonant circuits change impedance with change of frequency.

It has been stated before that the series resonant circuits 5-6 and 7-8 are oppositely mistuned by substantially equal frequency amounts with respect to the center frequency F_c of the applied FM waves. While it is not believed necessary to give specific frequency values, those skilled in the art know that for receiving standardized FM transmitters in the United States the frequency of circuit 5-6 may be removed some 75 kilocycles (kc.) or more from F_c . The frequency of circuit 7-8 may be correspondingly located 75 kc. or more on the opposite side of F_c . However, by tuning the series resonant circuits apart by a greater amount, and utilizing sufficiently broadly tuned circuits, less distortion in the demodulated output from the demodulator may be obtained. Thus, by broadening the circuit tunings and setting the tuning peaks further apart in frequency in a manner to reduce the percentage differential response of the circuit to a given change of frequency, the distortion of the detector network output may be reduced. Additional information on this subject will be found in my application Serial No. 297,777 filed October 4, 1939, which is a division of my U. S. Patent 2,179,182 granted November 7, 1939.

Where the receiving system is of the superheterodyne type, which is the type universally employed in present-day FM broadcast reception, the input circuits of the rectifier tubes will be operating at a lower, or I. F., value. Such I. F. value would generally be chosen from a range of between 2 and 8 megacycles (mc.). The assigned FM broadcast band in the United States at the present time is 42 to 50 mc., and the permissible channel width is 200 kc. As is well known, a carrier is deviated a maximum of substantially 75 kc. to either side thereof, and, hence, in the best receivers the inter-tube networks preceding the demodulator are designed to transmit nearly equally a band width of approximately 150 kc plus twice the band width of the modulation frequencies. It will be understood that the primary circuit of input transformer 4, which is magnetically coupled to the series resonant circuits, will be tuned to F_c , but will be a broad band circuit capable of responding substantially equally to the whole signal band.

The primary circuit of transformer 4 may be arranged in the anode circuit of the last I. F. amplifier stage. It is not believed necessary to describe the networks between the conventional signal collector and transformer 4, since these may follow standard FM broadcast superheterodyne receiver practice. Those skilled in the art are fully aware of the construction thereof. It is to be clearly understood that in the present case no amplitude limiter need be utilized in the system preceding the input to the demodulator at the primary winding of transformer 4. When no limiter is employed, it will be clear that there will be impressed upon the series resonant circuits 5-6 and 7-8 the FM waves whose carrier

has imposed thereon amplitude modulation components. Therefore, in the output circuit of the rectifiers, and prior to the input electrodes of tube 1, there will appear the undesired amplitude modulation components. Nevertheless, the construction and functioning of tube 1 are such that in the output circuit thereof the amplitude modulation components will not appear, or will be of greatly reduced relative strength. It will be recognized that this is entirely different from the practice which has been followed in the prior art.

It is not believed necessary to explain the manner in which the detector functions. It is sufficient to point out that when the signal energy applied to the series resonant input circuits have an instantaneous frequency equal to the value F_c , the audio voltages across load resistors 12 and 11 will be equal, but of opposite polarity. In other words, the cathode ends of each of resistors 11 and 12 will have like polarity. When the instantaneous frequency of the applied signal energy shifts away from F_c , there will be developed across one of the load resistors more rectified potential. Of course, that load resistor will have a greater magnitude of rectified potential thereacross which corresponds to the series resonant input circuit whose resonant frequency is being departed from by the aforementioned instantaneous frequency. In other words, for frequency deviation from F_c , the cathode ends of resistors 11 and 12 will be of like polarity, but of unlike magnitude. Of course, the carrier amplitude variations will affect both ends of resistors 11 and 12 to substantially the same percentage magnitude.

It is to be understood that the present invention is applicable to any other type of balanced FM detector circuit. For example, the resistors 11 and 12 could be placed in the output circuits of the demodulator disclosed in the aforementioned Usselman patent. Again, the resistors could be placed in the output circuits of the demodulator described in the aforementioned Seeley patent. Whatever the construction of the demodulator circuit, it is only required that the opposite ends of the series-related load resistors be at potentials of like polarity, but of unlike magnitude as a result of detection of frequency, or phase, modulations of modulated carrier waves.

There will now be considered the circuit which includes the potential ratio-controlled amplifier. The amplifier tube 1 is schematically represented in Fig. 1. In Figs. 2, 3 and 4 the electrode structure thereof is more specifically shown. In general, the tube 1 is of the type shown in my application Serial No. 324,053 filed March 15, 1940. However, there are certain modifications and improvements involved in the tube structure as well as in the use of the tube in this present application.

Within the tube envelope of tube 1 there is provided an electron emission element 13, which has the electron stream therefrom passed through an opening in the end of an anode electrode 14. The anode electrode 14 is connected to the positive point 15 on the direct current power supply potentiometer P. It is to be understood that the positive and negative terminals of the potentiometer P may be connected to any desired direct current energizing source. The emission electrode 13 is connected to the negative terminal of the potentiometer. The electrons are projected from the anode 14 in the form of an electron beam. The beam is passed in a median position between a pair of divergent rod-

like electrodes 16 and 17. The electrodes 16 and 17 are located within the interior of an enveloping cylindrical electrode 18 whose rear end 19 is provided with a central foraminous, or screen, section through which electrons may pass to either of a pair of collection electrodes 20 and 21. The electrode 18 may be tapered, as shown in Fig. 2.

The electron collectors 20 and 21 are connected to opposite ends of the primary winding of audio output transformer 22. The midpoint of the primary winding is connected to the positive terminal of potentiometer P. A shield electrode 23 projects from the end 19 of cylinder electrode 18, and acts as an electrical shield between electrodes 20 and 21. The cylinder 18 is connected to potential point 15, and hence, is at the same potential as anode 14. The forward end of cylinder 18 is open so that the electron beam readily passes through the open end into the field between electrodes 17 and 16. The electrode 17 is connected to the cathode end of resistor 12 by condenser 30, while condenser 31 couples the electrode 16 to the cathode end of resistor 11.

Resistor 32 is connected in shunt with load resistor 11-12, and between condensers 30 and 31. The midpoint of resistor 32 is connected to a point 33 on P which is at a negative potential relative to point 15. Hence, the electrodes 17 and 18 are normally, and in the absence of applied signals, at an equal direct current potential which is less positive than point 15 and the positive end of potentiometer P. Before explaining the functioning of the potential ratio-controlled amplifier circuit, the detail structure of the tube will be considered. As stated previously, the representation of tube 1 in Fig. 1 is purely schematic. Hence, Figs. 2, 3 and 4 should be considered in connection with tube 1.

The tube envelope 40 may be made of glass, metal or other suitable material. Preferably, the envelope has a constricted section in which is located the electron emitter 13 and heater element 13'. The anode 14 is shown as a hollow cylinder surrounding the emitter. The electrons are projected into the flared main body of the tube through the aperture 14' in the forward end of the anode. The electrodes 16 and 17 are each long rods of circular cross-section. They diverge in the manner shown in Fig. 2. Leads 17' and 16' connect rods 17 and 16 respectively to coupling condensers 30 and 31. The numeral 50 denotes the electron beam which passes to the end 19 of the shield can 18. The can 19 is metallic, as are the rods 17 and 16. The can 19 tapers towards its open input end. Since the shield 18 is a hollow cylinder which envelopes the rods 17 and 16, the closed end 19 has a circular shape.

The end wall 19 is provided with a circular screen 19', or grid-like mesh, through which electrons may pass to the spaced collector electrodes 20 and 21. The screen has its wires preferably parallel to the direction of beam deflection. Across the diameter of the screen 19' is secured a lateral metallic, electric shield 23. The latter is located between the collectors 20 and 21 in spaced relation thereto. Each collector is a hollow box. One long side of the box is open, and spaced from the foraminous screen 19'. The conductors from the collectors pass to respective opposite ends of the primary winding of audio transformer 22. Fig. 4 shows the relation between the electrodes when viewed from the collectors towards the emission electrode. The electric shield 23 extends beyond the limits of the

spaced parallel collectors. The conductors from the collectors 20 and 21 are designated by the numeral 51. These conductors are connected to the respective ends of the primary winding of audio transformer 22.

Referring to Fig. 3 there is shown in cross-section the electrodes 16, 17 and 18, and the approximate configuration of an electric field between them. Fig. 3 shows how the enveloping cylinder 18 surrounds the two rod-like electrodes 17 and 16.

The electrodes 16 and 17 are indicated as negatively charged with respect to the cylindrical electrode 18. With this arrangement as it is indicated in Fig. 3, there will be a region of substantially zero transverse electric field midway between the two rods 16 and 17. This region of zero transverse electric field can be moved toward or away from each of electrodes 16 and 17 by giving to the latter a difference in negative potential. As has been explained previously, the electrodes 16 and 17 are connected to point 33 of potentiometer P, point 33 being a substantially negative potential point.

Assume, now, that a stream of electrons 50 is passing along the axis of the cylindrical electrode 18 midway between the two rod electrodes 16 and 17. There will be substantially no tendency for the electron stream to be accelerated in any transverse direction so long as it is traveling in the region of substantially zero transverse electric field. However, if for any reason the stream is deflected toward one or the other of the rod-like electrodes, it will come within an electric field which tends to return it to the line, or region, of zero electric field.

Therefore, to a fair degree of approximation, when the potentials on electrodes 16 and 17 are equal, and when the electric fields are strong enough compared with electron velocities, elec-

trons can flow only within the region of a plane which bisects the cylindrical electrode at right angles to a line connecting the electrodes 16 and 17. In other words, the electron stream 50 is constrained to flow within the region of substantially zero transverse electric field. Accordingly, if we apply different electric potentials to the electrodes 16 and 17, thereby deflecting the region of zero transverse electric field, the path which can be taken by the electron stream may be controlled. Within a large range of potentials this path may be made substantially independent of the total potentials upon the rod electrodes with respect to the cylindrical electrode 18, but dependent substantially upon their ratio. That is why the amplifier 1 has been referred to as a "potential ratio-controlled amplifier."

Therefore, if the negative potential applied to each of electrodes 16 and 17 is obtained from one side of a balanced FM detector, it is possible to make the path taken by the electron streams substantially dependent upon the frequency of current input to a balanced FM detector, but nearly independent of the amplitude of signal input to the balanced detector. It is to be clearly understood that while I have shown a particular type of amplifier tube construction for tube 1, other types of tube structure operating on the same principles may be used. For example, any of the tube structures shown in my aforesaid pending application Serial No. 324,053 may be utilized in place of the particular tube structure shown herein. Again, it is to be understood that the detail configurations of the electrodes 16, 17 and 18 are not essential, since other configurations may be utilized. For example, the rod elec-

trodes 16 and 17 may be shaped in different modes in order to provide different laws of control over the electron stream 50.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In combination with a detector of angular velocity-modulated carrier waves adapted to produce a pair of independent voltages which correspond to modulation of the carrier waves, and which voltages are of like polarity relative to a common reference voltage point but of different magnitude, an electron discharge tube comprising an electron emission element, a pair of electron collector electrodes, a modulation voltage utilization circuit coupled to said collector electrodes, means confining the electrons emitted from said emission element to an electron beam projected toward said collector electrodes, at least two beam control electrodes in spaced relation on opposite sides of said beam, said control electrodes diverging in the direction of said collector electrodes, means for applying the aforesaid modulation voltages of differing magnitude to respective ones of said control electrodes, and means for maintaining said spaced control electrodes at a normal negative potential with respect to said collector electrodes whereby said electron beam is constrained to flow within a limited region between the two control electrodes.

2. In combination with a detector of angular velocity-modulated carrier waves adapted to produce a pair of independent voltages which correspond to modulation of the carrier waves, and which voltages are of like polarity relative to a common reference voltage point but of different magnitude, an electron discharge tube comprising an electron emission element, a pair of electron collector electrodes, a modulation voltage utilization circuit coupled to said collector electrodes, means confining the electrons emitted from said emission element to an electron beam projected toward said collector electrodes, at least two beam control electrodes in spaced relation on opposite sides of said beam, said control electrodes diverging in the direction of said collector electrodes, means for applying the aforesaid modulation voltages of differing magnitude to respective ones of said control electrodes, means for maintaining said spaced control electrodes at a normal negative potential with respect to said collector electrodes whereby said electron beam is constrained to flow within a region midway between the two control electrodes, and a cylindrical electrode surrounding said spaced control electrodes, said cylindrical electrode being maintained at a positive potential with respect to the potentials of said spaced control electrodes.

3. In combination with a balanced frequency modulation carrier wave detector adapted to provide a pair of independent modulation voltages of like polarity relative to a common reference voltage point and differing magnitude, an amplifier tube for said modulation voltage which is insensitive to carrier amplitude variation, said amplifier comprising an electron emission element, means for producing an electron beam from electrons emitted from said element, a pair of spaced rod-like electrodes arranged on respectively op-

posite sides of the electron beam and being divergent, a pair of spaced collector electrodes, a modulation voltage utilization circuit connected in push-pull relation to said collector electrodes, a hollow cylindrical electrode enveloping said rod-like electrodes, means for maintaining the latter electrodes at a negative potential relative to the enveloping cylinder and said collector electrodes whereby said electron beam passes along the axis of the cylindrical electrode midway between the rod-like electrodes, and means for applying the aforesaid modulation voltages to the respective ones of said rod-like electrodes, said cylindrical electrode having the end thereof adjacent said collector electrodes provided with an electron-transmitting screen.

4. In combination with a detector of angular velocity-modulated carrier waves adapted to produce a pair of independent voltages which correspond to modulation of the carrier waves, and which voltages are of like polarity relative to a common reference voltage point but of different magnitude, an electron discharge tube comprising an electron emission element, a pair of electron collector electrodes, a modulation voltage utilization circuit coupled to said collector electrodes, means confining the electrons emitted from said emission element to an electron beam projected toward said collector electrodes, means for establishing an electric field which forces electrons in the beam toward a plane of minimum transverse electric field, and means for applying the aforesaid modulation voltages of differing magnitude to vary the electric field for varying the position of the plane.

5. In combination with a detector of angular velocity-modulated carrier waves adapted to produce a pair of independent voltages which correspond to modulation of the carrier waves, and which voltages are of like polarity relative to a common reference voltage point but of different magnitude, an electron discharge tube comprising an electron emission element, a pair of electron collector electrodes, a modulation voltage utilization circuit coupled to said collector electrodes, means confining the electrons emitted from said emission element to an electron beam projected toward said collector electrodes, at least two divergent control electrodes in spaced relation on opposite sides of said beam, means for applying the aforesaid modulation voltages of differing magnitude to respective ones of said control electrodes, means for maintaining said spaced control electrodes at a potential with respect to said collector electrodes whereby said electron beam is constrained to flow within a region midway between the two control electrodes, a cylindrical electrode surrounding said spaced control electrodes, and said cylindrical electrode being maintained at a positive potential with respect to the potentials of said spaced control electrodes.

6. In combination with a detector of frequency modulated carrier waves adapted to produce a pair of independent voltages which correspond to modulation of the carrier waves, and which voltages are of like polarity relative to a common reference voltage point but of different magnitude, an electron discharge tube comprising an electron emission element, a pair of electron collector electrodes, a modulation voltage utilization circuit coupled to said collector electrodes, electrons emitted from said emission element being in the form of an electron beam projected toward said collector electrodes, means for establishing a region of low transverse electric field through

which said beam is constrained to pass, and means for utilizing the aforesaid modulation voltages of differing magnitude to move the position of the region thereby to deflect the position of the beam.

7. In combination with a balanced detector of frequency modulated carrier waves adapted to produce voltages of differing magnitude which correspond to modulation of the carrier waves, an electron discharge tube comprising an electron emission element, a pair of collector electrodes, a modulation output circuit coupled to said collector electrodes, means forming the electrons emitted from said emission element into an electron beam projected toward said collector electrodes, at least two control electrodes in spaced relation on opposite sides of said beam, said control electrodes diverging towards said collector electrodes, means for applying the aforesaid modulation voltages to respective ones of said control electrodes, and means for maintaining said spaced control electrodes at a potential with respect to said collector electrodes such that said electron beam is constrained to flow within a limited region between the two control electrodes.

8. In combination with a source of a pair of independent voltages of like polarity relative to a common reference voltage but of different magnitude, an electron discharge tube comprising an electron emission element, a pair of electron collector electrodes, an output circuit coupled to said collector electrodes, means confining the electrons emitted from said emission element to an electron beam projected toward said collector electrodes, at least two beam control electrodes in spaced relation on opposite sides of said beam, said control electrodes diverging in the direction of said collector electrodes, means for applying the aforesaid voltages of differing magnitude to respective ones of said control electrodes, means for maintaining said spaced control electrodes at a normal negative potential with respect to said collector electrodes whereby said electron beam is constrained to flow within a region midway between the two control electrodes, and a cylindrical electrode surrounding said spaced control electrodes, said cylindrical electrode being maintained at a positive potential with respect to the potentials of said spaced control electrodes.

9. In an amplifier system which is insensitive to current amplitude variation, an electron emission element, means for producing an electron beam from electrons emitted from said element, a pair of spaced rod-like electrodes arranged on respectively opposite sides of the electron beam and being divergent, a pair of spaced collector electrodes, a voltage output circuit connected in push-pull relation to said collector electrodes, a hollow cylindrical electrode enveloping said rod-like electrodes, means for maintaining the latter electrodes at a negative potential relative to the enveloping cylinder and said collector electrodes whereby said electron beam passes along the axis of the cylindrical electrode midway between the rod-like electrodes, means for applying voltages to be amplified to the respective ones of said rod-like electrodes, said cylindrical electrode having the end thereof adjacent said collector electrodes provided with an electron-transmitting screen.

10. In combination with a balanced frequency modulation detector, an amplifier insensitive to amplitude variation of detected voltages, said amplifier including a pair of spaced rod-like electrodes means for controlling the position of a beam of moving electrons substantially in accordance with the ratio of potentials on said two electrodes, but substantially independently of the sum of the potentials on the two electrodes, means for employing the electrode potentials to establish a plane of minimum electric field in directions transverse to the general direction of the beam, and means to vary the ratio of the potentials.
11. In combination, an electron discharge tube comprising an electron emission element, a pair of electron collector electrodes, a signal voltage utilization circuit coupled to said collector electrodes, electrons emitted from said emission element being in the form of an electron beam projected toward said collector electrodes, means for establishing a region of low transverse electric field through which said beam is constrained to pass, and means for utilizing signal voltages of differing magnitude to move the position of the beam.
12. In a receiver of angular-velocity modulated carrier waves, a demodulator for producing a pair of independent modulation voltages from said waves, an amplifier following the demodulator, said amplifier including means to provide an electron beam, means for establishing a region of low transverse electric field through which said electron beam is constrained to pass, and means responsive to said voltages to move the position of the beam.
13. In combination with a detector of angular velocity-modulated carrier waves adapted to produce a pair of independent voltages which correspond to modulation of the carrier waves, and which voltages are of like polarity relative a reference voltage point but of different magnitude, an electron discharge tube comprising an electron emission element, a pair of electron collector electrodes, a modulation voltage utilization circuit coupled to said collector electrodes, means for establishing an electric field which forces electrons in the beam toward a plane of minimum transverse electric field, and means for varying the electric field in response to said voltages for varying the position of the plane.
14. In an electronic system, means adapted to provide at least two potentials, an electron vacuum tube including means for producing a beam of moving electrons, means for establishing a configuration of electric fields within said tube which tend to determine the path of the electrons and to oppose any motions away from said path, at least two spaced electrodes responsive respectively to said potentials for modifying the configuration of the electric fields to bend the path, at least two anodes in said tube for collecting the electrons with a distribution of numbers between the anodes which is determined by the bending of the path in response to the ratio of said two potentials substantially independently of their magnitudes over a substantial range.
